MOCCASIN

Louis W. Simister, Astoria, N. Y.

Application March 14, 1936, Serial No. 68,806

1 Claim. (Cl. 36—11)

This invention relates to foot wear and particularly to that variety of light shoes and slippers known as moccasins.

An object of the invention is to provide a comfortable moccasin, consisting of few and simple parts so designed and constructed that these parts may be assembled from proper blanks, by any person without previous experience.

A further feature is in the provision of a moccasin that may be made in various sizes.

Another purpose is to produce a moccasin of attractive appearance from blanks precut, entirely without stitching, nailing or otherwise securing the parts in predetermined position except for the lacing means employed.

These advantageous objects are attained by the novel design, construction and combination of parts hereinafter described and illustrated in the annexed drawing, constituting an essential component of this disclosure, and in which:—

Figure 1 is a plan view of a blank forming the main body of a moccasin made in accordance with the invention.

Figure 2 is a similar view of the blank constituting the upper.

Figure 3 is a like view of the heel counter.

Figure 4 is a plan view of the blank from which the ornamental bow is formed.

Figure 5 is a perspective view of the moccasin as fully assembled.

Figure 6 is a longitudinal sectional view taken on line 6—6 of Figure 5; and

Figure 7 is a fragmentary perspective view of the heel portion of the moccasin prior to final assembly.

Referring in greater detail to the drawing, the view shown in Figure 1 includes a central sole portion 15 extending from toe to heel, this element being demarcated by a marginal row of narrow slot-like apertures 16.

The rear portion of this blank has its lateral edges extended to form reverse folds 17 at the heel, these folds having similar apertures 18, and their extreme outer edges are preferably fancifully formed as at 19.

Centrally of the rear portion of the blank are spaced cuts 20 having between them a tab 21 foldable upwardly at the ends of the cuts.

The moccasin upper, indicated in Figure 2, is generally oval in plan, its rear portion 25 having scalloped edges 26. The forward part 27 of the blank is provided with a marginal row of radially disposed elongated perforations 28, and centrally, at its upper end, a pair of slots 29 are formed, producing between them a loop 30.

In Figure 3 is seen a counter or stiffening shank at the heel, the blank 32 being generally

the shape of a truncated cone and in its narrower portion are two sets of openings 33—34.

An ornament, as the bow blank 35, seen in plan in Figure 4, is adapted to be disposed under the loop 30, the ends of the bow blank being 5 fancifully formed, as at 36.

In assembling these several parts, a common flat shoe lace 38, or its equivalent, is employed as a securing means.

The blank 15 is maneuvered to present up- 10 standing edges 15', the bend occurring inside the line of apertures 16; the side folds 17 are turned downwardly, and the rear of the moccasin formed by bending the blank so that its straight rear edges are approximately in contact. 15

The counter 32 is formed to extend at its narrow end into the pocket formed by bending the blank device while the wider, upper end 32' is turned down over the adjacent end edges 15' of the main blank, and the tab 21 is folded there- 20 over; the counter may, if preferred, be secured in place by any suitable adhesives.

The upper 27 is assembled and the lacing 38, beginning at the back, is threaded through the apertures 21', then through the openings 33—34 25 continuing towards the front through apertures 16 and 18, then through the openings 16 and 28 in the upper, around the toe and back on the opposite side in similar sequence.

From the foregoing, it will be understood that 30 the material is of a flexible nature, that the several perforations in the adjoining parts must match, and that a single, fastening member alone is used in securing and maintaining the moccasin in condition to impart comfort to the 35 wearer, and present a comely appearance.

Although the foregoing is descriptive of the preferred embodiment of the invention, it will be apparent that minor changes may be made in its construction without the exercise of invention or conflicting with the scope of the claim hereto appended.

Having thus described the invention, what is claimed as new and desired to secure by Letters Patent, is:

A moccasin comprising a main blank having a semioval front, a rectangular rear portion and a substantially straight rear edge, said blank having a single row of marginal perforations, a counterblank having a row of perforations corresponding to the perforations in said main blank, an upper blank plurally perforated marginally in conformity with the perforations in the main blank, and a unitary lace passing through all the mentioned perforations and tied 55 at the back, whereby the moccasin is complete.

LOUIS W. SIMISTER.
